UNITED STATES PATENT OFFICE.

ERNEST RUBES, OF BROOKLYN, NEW YORK.

DESIGN FOR AN AUTOMOBILE-HORN.

Specification for Design.

Patented Jan. 9, 1912.

42,091.

Application filed March 26, 1910. Serial No. 551,810. Term of patent 7 years.

To all whom it may concern:

Be it known that I, ERNEST RUBES, a citizen of the United States, residing at Brooklyn, in the county of Kings, State of New York, have invented a new, original, and ornamental Design for an Automobile-Horn, of which the following is a specification, reference being had to the accompanying drawing, in which the figure is an ele-

vation of an automobile-horn, showing my new design.

I claim—

The ornamental design for an automobile horn, as shown.

ERNEST RUBES.
